MOTOR PLOW

George A. Branson, Mountain Home, Idaho

Application March 23, 1949, Serial No. 82,969

3 Claims. (Cl. 97—29)

1

The present invention relates to a farming machine and it consists in the combinations, constructions and arrangements of parts herein described and claimed.

Generally there is provided a farming machine comprising a frame or chassis at the rear end of which is mounted a single steering wheel and forwardly of the chassis there is provided a pair of drive wheels which are powered by a motor or engine carried upon the chassis. At the rear end of the frame or chassis there is provided an operator's seat and a steering column is positioned immediately forwardly of such seat. There is provided a plurality of plows which may be manipulated by means of levers handy to the operator of the machine and the plows may be raised and lowered in a novel manner and there is also provided at the forward end of the chassis a bulldozer blade which may also be raised and lowered by means of a lever adjacent the operator's seat. Other novel features are also embodied in the invention and will be set forth more specifically hereinafter.

It is accordingly an object of the invention to provide a machine of the character set forth which is comparatively simple in construction, easy to operate and yet effective and efficient in use.

Another object of the invention is the provision, in a machine of the character set forth, of novel means for controlling a plurality of plows forming a part of the invention.

Another object of the invention is the provision, in a machine of the character set forth, of a novel bulldozer blade forming a part of the invention and novel means for the control thereof.

Another object of the invention is the provision of a novel mounting for a plowshare.

Other and further objects of the invention will become apparent from a reading of the following specification taken in conjunction with the drawings, in which:

Figure 1 is a side elevational view of an embodiment of the invention.

Figure 2 is a plan view of Figure 1.

Figure 3 is an enlarged sectional view taken along line 3—3 of Figure 1.

Figure 4 is a fragmentary elevational view illustrating certain details of construction.

Figure 5 is a sectional view taken along line 5—5 of Figure 4.

Figure 6 is a sectional view taken along line 6—6 of Figure 4.

Figure 7 is an enlarged fragmentary sectional view taken along line 7—7 of Figure 2,

2

Figure 8 is a fragmentary end elevational view of Figure 7.

Figure 9 is a sectional view taken along line 9—9 of Figure 10.

Figure 10 is a plan view of the machine embodying the present invention with its plows in upraised position with a bulldozer in place thereon, and with certain spring clips shown in Figures 2 to 5, inclusive, removed therefrom.

Referring more particularly to the drawings, there is shown therein a frame or chassis which extends horizontally and which comprises a pair of rear side members 10 and 11 and a pair of forward side members 12 and 13. The members 10 and 11 are interconnected at their rear end by a transversely extending cross bar 14 and at their forward ends by a like member 15.

A steering block 16 is affixed to the frame immediately forwardly of the cross bar 14 and a vertically extending steering column 17 extends therethrough and terminates at its lower end in a yoke 18 for a steering wheel 19 which also acts to support the apparatus forming the present invention. The upper end of the steering column 17 is provided with the conventional tiller wheel 20 and a bracket 21 is supported upon the frame at the rear end thereof to carry a seat 22 for the operator of the apparatus.

Extending forwardly from the block 16 and likewise forming a part of the frame or chassis of the apparatus is a pair of parallel, centrally disposed longitudinally extending keel members 23 and 24 whose forward edges are in alignment with the forward edges of the side members 12 and 13.

A transversely extending strut 25 interconnects the rear end of the side member 12 and the keel 23 and a like strut 26 interconnects the rear end of the side member 13 and the keel 24.

A pair of longitudinally extending frame members 27 and 28 interconnect the strut 25 and the cross bar 15 and the strut 26 and the cross bar 15, respectively. The members 27 and 28, while forming a part of the sides of the chassis are nevertheless inset from the planes of the side members 10, 12, 11 and 13 to thereby provide recesses 29 and 30 for drive wheels 31 and 32, respectively, which wheels are mounted upon an axle 33 affixed to the undersides of the keels 23 and 24.

An engine 34 is mounted atop the keels 23 and 24 and is provided with a pair of rearwardly extending control rods 35 and 36 which extend through an upright support member 37 adjacent the steering column and terminate in fingerpieces 38.

A shaft 39 having a crank 40 centrally disposed therein is journalled forwardly in the side member 10 and extends transversely of the chassis and is journalled at its other end in the keel 23. A transversely extending shaft 41 having a centrally disposed crank 42 is journalled forwardly in the side member 11 and in the keel 24.

A shaft 43 having a crank 44 is journalled in the forward end of the side member 12 and in the keel 23 and a like shaft 45 is journalled in the forward end of the side member 13 and in the keel 24 and is provided with a crank 46. The shafts 39 and 41 are respectively provided with upwardly extending levers 47 and 48 and the shafts 43 and 45 are respectively provided with upwardly extended arms 49 and 50.

A horizontally extending link 51 is provided at its rear end with a yoke 52 which is connected pivotally with the lever 47 and at its forward end with a yoke 53 which is pivotally connected adjacent the upper end of the arm 49.

A horizontally extending link 54 is provided at its rear end with a yoke 55 which is pivotally connected to the lever 48 and at its forward end with a yoke 56 which is pivotally connected to the upper end of the arm 50.

A toothed segment 57 is affixed upon the upper side of the member 10 adjacent the lever 47 and a toothed segment 58 is affixed to the upper side of the member 11 adjacent the lever 48. Each of the levers 47 and 48 is provided with a latch 59 and 60, respectively, which latches are adapted to be manipulated by means of levers 61 adjacent the upper ends of the levers 47 and 48.

A plow 62 is affixed to the rearward end of a shaft 63 whose forward end is provided with a yoke 64 which is, in turn, revolvably connected with the crank 44 and held in position thereon by means of a spring latch member 65. A plow 66 is likewise carried at the rear end of a shaft 67 provided with a yoke 68 which is revolvably connected with the crank 46 and latched thereto by means of a spring latch member 69. A plow 70 is affixed to the rear end of a shaft 71 which is provided at its forward end by a yoke 72 which is revolvably connected with the crank 40 and latched thereto by means of the spring device 73. A plow 74 is carried at the rear end of a shaft 75 which is provided at its forward end with a yoke 76 which is revolvably connected with the crank 42 and held in position thereon by means of the spring device 77.

Each of the shafts 63, 67, 71 and 75 is formed with a downwardly curved portion 78 at its rear end, a horizontally extending integral portion 79 and an angularly and upwardly extending portion formed integrally with the portion 79, as indicated at 80.

A transversely extending shaft 81 having a crank 82 is centrally journalled in the side member 12 and in the keel 23 and the crank 82 extends beneath the plow shaft 63. A transversely extending shaft 83 is centrally provided with a crank 84 and is centrally journalled in the side member 13 and the keel 24 and the crank 84 passes beneath the plow shaft 67. A transversely extending shaft 85 is centrally provided with a crank 86 which extends beneath the plow shaft 71 and the shaft 85 is centrally journalled in the side member 10 and in the keel 23. A transversely extending shaft 87 is centrally provided with a crank 88 which extends beneath the plow shaft 75 and is centrally journalled in the side member 11 and in the keel 24.

The shaft 81 is provided with an upwardly ex-

tending arm 89 and the shaft 83 is provided with a like upwardly extending arm 90. The shaft 85 is provided with an upwardly extending operating lever 91 and the shaft 87 is provided with an upwardly extending operating lever 92.

A horizontally extending elongated link 93 is provided at its rear end with a yoke 94 which is pivotally connected through the lever 91 and is provided at its forward end with a yoke 95 which is pivotally connected to the upper end of the arm 89. A horizontally extending elongated link 96 is provided at its rear end with a yoke 97 which is pivotally connected to the operating lever 92 and is provided at its forward end with a yoke 98 which is pivotally connected adjacent the upper end of the arm 90.

A toothed segment 99 is mounted atop the side member 10 adjacent the operating lever 91 and a like toothed segment 100 is mounted atop 20 the side member 11 adjacent the operating lever 92.

Each of the cranks 82, 84, 86 and 88 is provided with a bearing assembly comprising, in each case, a roller 101 mounted revolvably upon the crank and provided with a centrally disposed peripheral groove 102 in which the horizontal portion 79 of the plow shaft is adapted to rest. An inverted U-shaped spring clip 103 is provided with curled ends 104 adapted to receive a U-shaped locking pin 105 therein. A second roller 106 provided with a peripheral groove 107 is mounted upon an axle 108 which extends through the sides of the member 103 and the second roller 106 is adapted to rest upon the upper side 30 of the horizontal portion 79 of the plow shaft.

In operation, it will be apparent that the plows 62 and 70 may be raised and lowered by means of the lever 91 and that the plows 66 and 74 may be raised and lowered by means of the lever 92. 40 The apparatus may be utilized without the scoop 109 in position in which case it will act as an adjustable plow or cultivator. When desired, the plows may be raised to the position shown, for example, in Figure 9 and thereafter the pins 119 and 121 may be inserted through the openings provided therefor after which the plow shafts 63, 67, 71 and 75 will be supported by the pins 119 and 121.

While but certain forms of the invention have 50 been shown and described herein, it will be readily apparent to those skilled in the art that many minor modifications may be made without departing from the spirit of the invention or the scope of the appended claims.

What is claimed is:

1. An apparatus of the character described comprising a horizontal frame having a recess centrally in each side thereof, a drive wheel in each of said recesses, an axle for said drive wheels carried by the frame, an engine for supplying power to the drive wheels mounted on the frame over said axle, a vertically extending steering column mounted centrally adjacent the rear of the frame, a dirigible supporting wheel at the 60 lower end of the steering column, an operator's seat mounted upon the frame adjacent the steering column, a pair of plows mounted adjacent the forward end of the frame and below the sides thereof, a pair of plows mounted adjacent the 65 rearward end of the frame and inwardly from the sides thereof, manually operable means for raising and lowering the plows on one side of the frame, and independent manually operable means for raising and lowering the plows on the 70 other side of the frame.

2. An apparatus of the character described comprising a horizontal frame having a recess centrally in each side thereof, a drive wheel in each of said recesses, an axle for said drive wheels carried by the frame, an engine for supplying power to the drive wheels mounted on the frame over said axle, a vertically extending steering column mounted centrally adjacent the rear of the frame, a dirigible supporting wheel at the lower end of the steering column, an operator's seat mounted upon the frame adjacent the steering column, a pair of plows mounted adjacent the forward end of the frame and below the sides thereof, a pair of plows mounted adjacent the rearward end of the frame and inwardly from the sides thereof, manually operable means for raising and lowering the plows on one side of the frame, independent manually operable means for raising and lowering the plows on the other side of the frame, and manually operable means for locking said plows in raised positions.

3. An apparatus of the character described comprising a horizontal frame having a recess centrally in each side thereof, a drive wheel in each of said recesses, an axle for said drive wheels carried by the frame, an engine for supplying power to the drive wheels mounted on the frame over said axle, a vertically extending steering column mounted centrally adjacent the rear of the frame, a dirigible supporting wheel at the lower end of the steering column, an operator's seat mounted upon the frame adjacent the steering column, a pair of plows mounted adjacent the forward end of the frame and below the sides thereof, a pair of plows
